Primary Examiner—Cathy Anne MacCormac*Attorney, Agent, or Firm*—Morgan & Finnegan, LLP**[57]****CLAIM**

The ornamental design for the audio cassette tape case, as shown and described.

DESCRIPTION

FIG. 1 is a front perspective view of the audio cassette tape case in accordance with present invention;

FIG. 2 is another front perspective view of the audio cassette tape case in a using condition showing in dotted lines an audio cassette partially withdrawn from the audio cassette tape case;

FIG. 3 is a top plan view of the audio cassette tape case of FIG. 1;

FIG. 4 is a bottom plan view of the audio cassette tape case of FIG. 1;

FIG. 5 is a front elevation view of the audio cassette tape case of FIG. 1;

FIG. 6 is a rear elevation view of the audio cassette tape case of FIG. 1;

FIG. 7 is a right side elevation view of the audio cassette tape case of FIG. 1; and,

FIG. 8 is a left side elevation view of the audio cassette tape case of FIG. 1.

The broken lines in FIG. 2 are for purposes of illustration and form no part of the claimed design.
